FLEXIBLE DIAPHRAGM FOR GAS METERS

Edward R. Gilmore, Pittsburgh, Pa., assignor to
Rockwell Manufacturing Company, Pittsburgh,
Pa., a corporation of Pennsylvania

Application October 27, 1944, Serial No. 560,655

5 Claims. (Cl. 73—279)

1

This invention relates to an improved flexible diaphragm structure, the present improvement being more particularly designed for use in the operation of gas consumption recording meters, and the subject matter of the present application constituting a continuation-in-part of the disclosure of a diaphragm of this type described and claimed in my co-pending application for patent, Serial No. 448,601, filed June 26, 1942, now abandoned.

It is the major object of this invention to provide a diaphragm for gas meters and other apparatus having certain novel features of construction and assembly of its several elements whereby the flexible diaphragm is effectively sustained against collapse in the pulsating action of the diaphragm and the functionally effective life thereof materially prolonged.

In prior art efforts to solve this problem in the gas meter field various methods have been suggested for attaching the diaphragm leather to the inner and outer relatively movable metallic sections of the diaphragm structure with a view to minimizing the deleterious effects of flexing or bending stresses in the leather as one of said sections, subject to differential gas pressures, alternately moves to positions at opposite sides of the plane of the other diaphragm section. However, such efforts have failed to fully meet requirements, as the free intermediate section of the diaphragm leather is not adequately sustained against collapse, and, in the pulsating action either reverses its curvature or is distorted from a substantially straight line condition at one end of the diaphragm stroke to a more or less sharply curved condition at the opposite end thereof. Such extreme alterations in the cross-sectional configuration of the flexible membrane or section of the diaphragm structure subjects the same to high bending strains and a tendency of the flexible membrane to collapse at an intermediate point in the stroke of the diaphragm.

Therefore, it is the aim of the present invention to successfully meet this difficulty, and to this end I have found that by pre-forming the free section of the flexible membrane of the diaphragm, together with the provision of certain novel cooperating structural features of the metallic sections of the diaphragm structure, a free rolling action of said membrane is obtained in the pulsating stroke of the diaphragm which, in all positions thereof, is adequately self-sustained against collapse, and the severe bending, flexing or tensile strains, common to the prior art devices, are substantially eliminated. In func-

2

tional operation a substantially larger effective displacement of the pressure responsive area of the diaphragm is obtained, in comparison with a conventional diaphragm, for the same length of stroke.

Another object of the invention is to provide an outer mounting member for the diaphragm of improved structural form to which the outer edge of the flexible diaphragm membrane is attached and which will materially aid in sustaining said membrane against collapse during the operating stroke of the diaphragm.

It is also an additional object of the invention to provide an inner diaphragm section comprising metallic disks between which the central portion of the flexible leather or membrane is securely clamped, the peripheral edge portions of said disks being so constructed and related to each other that the wall of the membrane extending outwardly therebetween may have free radial movement relative to said peripheral portions of the disks, thus obviating sharp bending or flexing strains in the pulsating stroke of the diaphragm.

25 My invention also comprehends a novel pre-formed flexible leather or membrane to provide a comparatively self-sustaining impervious area thereof, subject to the gas pressure, having a predetermined gradual curvature axially of the diaphragm and in which there will occur a minimum alteration of such curvature in the operating stroke of the diaphragm.

Having the above and other subordinate objects in view, in the accompanying drawings I have illustrated one simple and practical embodiment of my present invention, which will hereinafter be more fully described and the several novel features thereof subsequently defined in the subjoined claims.

40 In the drawings, in which similar reference characters designate corresponding parts throughout the several views:

Figure 1 is a vertical section, partly in elevation, showing an extreme position of the diaphragm leather;

Figure 2 is a side elevation;

Figure 3 is a fragmentary sectional view, illustrating the rolling action of the diaphragm leather;

50 Figures 4, 5 and 6 are vertical sectional views progressively illustrating the several method steps in pre-forming the diaphragm by means of one suitable type of apparatus;

55 Figure 7 is an enlarged fragmentary sectional

view of the diaphragm clamping arrangement of the apparatus of Figures 4-6; and

Figure 8 is a diagrammatic view illustrating the increased effective displacement of my new diaphragm in relation to the displacement of a conventional prior art diaphragm.

With more particular reference to the drawings, for the purpose of this explanation, I have selected an example of my invention which embodies three primary sections comprising the outer fixed supporting section or diaphragm pan 10, the inner movable section or pressure receiving head 11, and the connecting flexible membrane, usually leather, section 12 attached to said inner and outer diaphragm sections. This general construction is, of course, characteristic of diaphragm structures of this type.

The outer section or pan 10 of the diaphragm structure includes an outwardly flaring circumferential wall 13, the edge of which is outwardly bent to form an open bead 14, from which a concave-convex annular flange 15 extends towards the base of the pan and has its concave face outwardly disposed. The free edge of this flange and the outer peripheral surface of the bead 14 are substantially tangential to a common horizontal plane. The particular advantage of this construction in the functional operation of the diaphragm will be hereinafter more fully explained.

To the outer surface of the pan wall 13, a suitably formed attaching bracket 16 is securely fixed and is adapted to be rigidly attached to the gas chamber wall of the meter. In circumferentially spaced relation from this bracket the wall 13 is also provided with a short outwardly extending conduit section 17 provided with suitably formed means at its end whereby it may be connected in coupled relation with the end of a conduit on the gas chamber wall so as to permit the gas flow through the customary channels of the meter casing.

While in the present instance I have shown this outer section 10 of the diaphragm structure in the form of a pan, it is to be understood that this section may also be embodied in the form of an annular metal plate having the flange 15 on its inner edge, as suggested by my co-pending application.

The diaphragm membrane 12 is preferably formed from a sheet of sheepskin, or any other suitable material having comparable flexible or pliable characteristics. In order that the purposes of my present invention may be fully attained it is essential that the area of the leather sheet, between its points of attachment to the outer and inner sections 10 and 11 of the diaphragm structure, be pre-formed to a predetermined shape, designed to render the area substantially self-supporting and resistant to collapse during flexure in normal operation, and in which area the original flexibility of the leather preferably remains substantially unaltered.

In Figures 4 to 7 of the drawings I have illustrated one embodiment of apparatus for producing a pre-formed diaphragm as above characterized. As therein shown, a fixed female die member 32 is rigidly mounted between spaced vertical guides 34 extending above said die member. The member 34 includes an outer cylindrical wall integrally connected at its upper end to the inwardly and downwardly conically tapering wall 36 by the annular, horizontal work supporting seat 38.

A male die carrying member is vertically mov-

able between the guides 34 above the fixed die member 32 and includes the cylindrical vertical wall 40 and a horizontal top wall 42, said member being open at its lower end to telescopically receive the cylindrical work clamping ring 44. At diametrically opposite points on the wall 42, spring housings 46 are suitably secured. To the upper ends of these housings rods 48 are fixed and extend downwardly therefrom through openings in inwardly projecting lugs 50 formed on the upper edge of the ring 44. Springs 52 bear at their lower ends against these lugs and at their upper ends against the top walls of the housings 46 and normally urge the ring 44 downwardly to the position seen in Figure 4 with respect to the wall 40 of the die carrying member, such movement of the ring being limited by heads 54 formed on the lower ends of the rods 48.

The male die preferably comprises a hollow bulbous member having a substantially semi-spherical lower end portion 56, preferably formed with a flat bottom face 58, and an inwardly tapering intermediate portion 60 merging into the cylindrical upper end portion 62 of reduced diameter, which is suitably fixed to the lower face of the top wall 42 of the die carrying member in concentric relation with the cylindrical wall 40 thereof.

A frame member 64 has spaced vertical legs 66 suitably fixed to a suitable supporting base and a horizontal connecting portion 68 between the upper ends of said legs, extending diametrically across the male die carrying member and vertically spaced therefrom. In a collar 70 centrally fixed to the frame portion 68, an adjusting screw 72 is threaded. Screw 72 is provided at its upper end with a suitable operating handle member 74 and at its lower end has a swiveled or rotatable connection 76 with the top wall 42 of the male die carrying member.

Preferably, suitable means is provided to limit the downward movement of the male die carrying member. As herein shown I provide the rod 78 fixed to said member and vertically movable through an opening in the frame 64. Upon the frame, a pivoted stop plate 80 is mounted and yieldingly urged by the spring 82 to engage a stop shoulder 84 formed on the rod 78.

For the purpose of increasing the ironing effectiveness of the clamping ring 44, I preferably form a shallow annular groove 86 in the lower edge face thereof adjacent to its inner cylindrical surface, said edge face being curved or tapered upwardly and radially outwardly from said groove to the outer cylindrical surface of the ring, as shown at 88 in Figure 7 of the drawings.

In each operation of the above described apparatus, I preferably form a plurality of the diaphragm members. The flat circular sheets 90 of leather or other flexible material of uniform thickness and of requisite surface area to form diaphragms of a predetermined diameter are first thoroughly damped with a mixture of alcohol and water. They are then assembled in superimposed relation and positioned with their marginal edge portions supported on the seat 38 of the female die member 32, as shown in Figure 4. Preferably, the de-haired side of the sheet is uppermost and in the finished diaphragm is on the outer side. In this figure the adjusting screw 72 has been operated to move the male die carrying member and ring 44 downwardly as a unit and position the bottom face 58 of the male die immediately above the central portions of the assembled sheets 90 and the lower edge of ring

44 substantially in contact with the marginal portion of the uppermost sheet.

Upon further operation of the adjusting screw, the male die and its carrying member are moved downwardly relative to the ring 44, the bottom face 58 of the male die engaging and depressing the central area of the flexible sheets into the female die. Simultaneously springs 52 are compressed to resiliently force the ring 44 downwardly and cause its lower edge face to apply a progressively increasing ironing or guiding pressure upon the marginal edge portions of the sheets, as shown in Figures 5 and 6 of the drawings, and the sheets are drawn over shaping edge 39 of the female die member. The pressure of ring 44 on the leather is only sufficient to prevent creases or wrinkles from forming in the leather sheet at the inner side of said ring in the depression of the male die member and is not sufficient to tensionally strain or stretch the leather.

As the male die is moved from the position of Figure 5 to that shown in Figure 6, the springs 52 are further compressed and the marginal portions of the sheets 90 drawn inwardly against the increasing resilient pressure resistance of the ring 44 as said sheets fold inwardly in an arc of progressively decreasing radius and finally assume an arcuate cross-sectional form molded about and corresponding to that of the semi-spherical portion 56 of the die member. This preforming operation produces the rather surprising result that under the preforming molding and ironing pressures the annular periphery of the sheet from which the diaphragm is formed is contracted in diameter, compacted and thickened slightly, constricting the material of the central portion of the diaphragm causing the excess material to form into a concavo-convex annular or semi-spherical section of the diaphragm, self-sustaining and non-collapsing in operation in a meter. Thus as seen in Figure 3, in the pulsating stroke of the head 11, in all positions thereof relative to the pan 10, this intermediate annular area A of the diaphragm extends in a large radius arc between the head 11 and rim 15 and in the same lateral direction relative thereto without abrupt change in curvature. While the changes which may occur in the physical structure of the diaphragm membrane or sheet to render the area A thereof self-sustaining are not known, such alteration or transformation of the fibrous sheet structure is thought to result from the fact that as the diameter of the sheet decreases wrinkles which would otherwise form are prevented by the ironing action of the surfaces 39 and 58 as the sheet is drawn inwardly against the resistance of pressure ring 44 and molded against the convex surface of plunger 60. Owing to the moist condition of the sheet, in this ironing action the individual fibres of the sheet are re-distributed and crowded together thus producing a substantially circumferentially uniform radial increase in density of the sheet structure as the constricted peripheral section decreases in diameter. This increase in density is accompanied by a slight increase in thickness, and by measurement it has been found that this increase in thickness and density in the diaphragm membrane progresses from the central region thereof to its marginal constricted section.

It will further be noted from reference to Figure 6 that the downward movement of the male die is so limited that the space between

the portion 56 thereof and the wall 36 of the female die 32 is always greater than the aggregate thickness of the several flexible sheets so that the arcuately curved portions of the sheets are not compressed between the two die members but are moulded snugly against the semi-spherical surface of male die. Thus, by carefully controlling the movement of the male die member, the flexible sheets are pre-formed without being subjected to appreciable tensile strain, and are maintained in a semi-spherical form free of wrinkles.

Preferably the predetermined axial curvature of the male die is substantially semi-spherical and this is the shape into which the annular area of the diaphragm sheet between the end region clamped at 18 and the region of beginning of curvature indicated at 30 is moulded by the above described operation. When the leather sheets are removed from the mold and separated, after having been dried, the compressed and moulded area of each, between regions 18 and 30, and identified at A has such substantially semi-spherical curvature in axial cross-section as illustrated in the lower part of Figure 1.

The diaphragm area A has substantially its original flexibility after the above described forming operation, any small increase in stiffness of the diaphragm material as a result of compression in the forming operation being more than compensated for by the reduced resistance to flexure during operation resulting from the smooth rolling action provided by the specially pre-formed shape of the diaphragm.

Of course when the formed leather sheet is operatively attached to the inner and outer sections of the diaphragm assembly, in the functional operation thereof, the area A does not assume the original curved form shown in Figure 1, but is maintained in a somewhat distorted shape as illustrated in Figure 3. This distortion, however, does not alter the imparted self-supporting qualities and resistance to collapse of area A or its smooth rolling action during axial flexure.

It is important that, in this pre-forming operation, no excessive heat be used, since this would produce a glaze on the surface of the leather sheet rendering the same unduly stiff or hard and preventing the closing of the pores in the leather by the customary oil treatment. The final treatment of the leather in an oil bath completely closes all pores therein and renders the same impervious to the passage of gas therethrough.

After the pre-forming of the leather sheet as above described, the outer edge portion thereof is trimmed off, and the outer marginal part of the pre-formed area A of the sheet is then seated upon the concave face of the flange 15 of the pan section 10 of the diaphragm and securely fixed thereto by the binding string, as indicated at 18, tightly wrapped about said marginal portion of the sheet and having the ends thereof tied or otherwise securely fixed to the clip member 18' rigidly attached to the pan wall 13.

The inner or central area B of the diaphragm leather, which remains in its original comparatively soft, pliable condition, is tightly clamped between the outer and inner metal disks 19 and 20, respectively. These disks are preferably of sheet metal of a suitable gauge, and the outer disk 19 is formed with an outwardly turned peripheral bead 21. The inner disk 20 is of somewhat greater diameter than the outer disk and has an outwardly flaring marginal flange 22 in

the plane of, and radially spaced from, the bead 21 on the disk 19. At its edge, the flange 22 is formed with the outwardly turned cylindrical bead 23.

While any preferred means might be employed to rigidly connect the two disks 19 and 20 and securely clamp the leather therebetween, I have shown for this purpose a central threaded bolt 24 having a head 25 on its inner end and a nut 26 threaded on the outer end thereof. This nut also secures a central portion of a bracket member 27 against the face of the plate or disk 19, which may be soldered at its upper and lower ends to the face of said disk, to securely hold the same against angular displacement relative thereto. This bracket member 27 is adapted to be connected by conventional means with an operating frame or member for the operating mechanism of the meter, whereby in the pulsating movements of the diaphragm sections 11 and 12, resulting from unbalanced fluid pressures on opposite sides thereof, said operating mechanism will be operated in the usual manner.

Reference should now be had to Figure 3 of the drawing, wherein I have illustrated the rolling action of the pre-formed free portion A of the diaphragm leather 12 in the pulsating stroke of the diaphragm. It will first be noted therefrom that in the movement of the inner diaphragm section 11, from the position shown in full lines to the broken line position at the end of the stroke at the extreme left, there is no change in axial direction of the inner part of said diaphragm leather attached to the section 11, but at both ends of the stroke the leather extends in the same direction from the outer periphery of the flange 22 and is not reversely turned over the bead 23 on said disk. Also in this movement of the diaphragm section 11, it will be apparent that owing to the spaced relationship between the flange 22 of the inner disk and the bead 21 on the outer disk, the part of the leather extending therebetween has free radial movement so that it is not subjected to sharp bending or flexing strains.

Secondly, the curved flange 15 and bead 14 on the fixed pan member 10, over which the edge portion of the pre-formed section A of the leather is positioned and secured, materially aids in sustaining the leather against collapse, this construction, in connection with the relatively compact fibre structure of the adjacent portion of the pre-formed diaphragm section A, effecting a distribution of the flexing of the leather over a longer radius curve in the stroke of the diaphragm than would be possible in the use of a conventional diaphragm having the marginal portion of the leather held or clamped between two flat surfaces. Thus, as will be seen from the drawing, at the points adjacent the connection of the leather with the inner and outer diaphragm sections, the leather, at all times, extends in the same axial direction from said sections and little flexing or bending of the leather occurs in the movement of the inner section 11 of the diaphragm structure from one end to the other of its stroke. It is at these points that structural deterioration and breakage or failure of the diaphragm leather, as used in prior art devices of this type, has most frequently occurred. In contradistinction, it will be seen that in the operation of the present invention only a gentle rolling action of the diaphragm leather takes place, which, throughout the pulsating stroke of the diaphragm, is adequately supported against col-

lapse, and in which there is no reversal of curvature or marked change in the cross-sectional configuration of the diaphragm leather to cause severe flexing or bending strains and the rapid ultimate destruction of the leather. I have found that by so pre-forming the leather 12 increased displacement by the diaphragm is obtained and the pulsating stroke of the diaphragm may be reduced in length with respect to the customary practice in this art, thus further reducing the destructive effects of bending of flexing strains. The invention also provides improved accuracy in calibration because of the ability of the diaphragm to undergo the same sequences of flexure with each stroke.

The substantial increase in effective displacement of the pressure responsive area of my new diaphragm membrane over that of the conventional non-processed membrane of the prior art, having a pulsating stroke of equal length, is graphically illustrated in Figure 8 of the drawings. Referring thereto, the lines 18 and 30, respectively, indicate the perimetrical portions of the outer mounting member and the inner movable pan between which the pressure responsive section of the flexible membrane extends. The inner and outer ends of the stroke of the movable pan are indicated at D and E, respectively. A plane perpendicular to the diaphragm stroke and coincident with the attached outer edge of the flexible membrane at 18 is indicated by the line K. Between the lines 18 and 30 the change in cross-sectional configuration of a conventional diaphragm in the outstroke of the inner pan member is shown at F, the volumetric displacement thereof being represented by the shaded area G. Similarly, lines H represent the cross-sectional configuration of my improved diaphragm membrane at the inner and outer ends 30 of the stroke while the shaded areas J plus G indicate the volumetric displacement thereof. It will be noted that, although the two diaphragms have substantially the same surface area, owing to the fact that the diaphragm of this invention has a smooth continuous rolling flexure in one direction and does not reverse its curvature or assume a straight line condition between the point E and line 18 at the outer end of the stroke, a much greater volumetric displacement is obtained than is possible in the operation of the conventional or standard type of diaphragm. Comparative tests have shown that this increase in volumetric displacement is at least as great as twelve per cent.

From the above description and accompanying drawings the several novel features of my present disclosure and the advantages thereof in practical operation will be readily understood. It will be appreciated that by means of my improvements I have succeeded in materially reducing the flexure or distortion of the diaphragm leather and the destructive effects thereof, while at the same time obtaining maximum accuracy and reliability in the functioning of said diaphragm for the operation of the recording meter. It is evident that these novel features of my present invention may be embodied in diaphragm structures of various sizes and designed for other uses than in connection with gas meters. The above described method of pre-forming the diaphragm leather may, of course, be carried out with the use of molding or blocking forms of various conventional or well known types, and while I have specifically referred to the manner in which this method is employed in pre-forming a

plurality of diaphragms or leathers, in some instances, a single leather diaphragm or sheet may be simultaneously pre-formed in a single operation of the molding apparatus.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A pre-formed diaphragm membrane comprising a circular sheet of fibrous non-elastic flexible material having a moulded, self-sustaining annular section of uniform arcuate cross-sectional configuration in all planes diametrically bisecting said sheet with a substantially uniform progressive increase in density and thickness of the fibrous structure from the inner to the outer perimeter of said annular section.

2. A gas meter diaphragm membrane comprising a single non-elastic sheet of sheep-skin or the like having an inner region thereof characterized by a substantially uniform fibre distribution throughout said region and a self-sustaining molded annular section circumscribing said inner region and normally having a substantially quadrant-shaped arcuate curvature in radial cross section, said annular section being characterized by increased density of its fibrous structure with respect to said inner region, progressively decreasing from its outer marginal portion to said inner region of the membrane.

3. The diaphragm membrane defined in claim 2 wherein said outer marginal portion comprises a diametrically constricted, compacted and thickened supporting section for said quadrant-shaped section normally disposed in a circumscribing plane substantially parallel with the plane of said inner region.

4. Diaphragm structure for gas meters and the like including an outer fixed annular member, a pulsatory inner member movable through said outer member between end positions materially spaced in opposite directions from the plane of said outer member, and a flexible connecting membrane attached to said members, comprising a single sheet of non-elastic fibrous material having an annular unattached portion

of progressively increasing fibre density and resistance to flexing stress to the outer attached margin of said membrane, and operating to sustain said membrane in curvilinear cross-sectional form convex in one direction in all positions of said inner member.

5. In a diaphragm assembly for a gas meter, a relatively stationary pan having an annular outer rim, an instrument connected head adapted for pulsatory movement through said rim between end positions materially spaced in opposite directions from said rim, and a connecting flexible membrane comprising a single sheet of flexible non-elastic material having its central portion clamped to said head, an annular outer region secured upon said rim and an intermediate free annular portion preformed to convex cross section and to have progressively increasing material density outwardly to said outer region adjacent said rim so that said intermediate membrane portion maintains convexity in the same direction during the entire range of pulsatory movement of said head.
